UNITED STATES PATENT OFFICE

RICHARD S. WALKER, OF PETERSBURG, VIRGINIA

SOAP DISPENSING DEVICE

Application filed March 7, 1928. Serial No. 259,852.

This invention is directed to an improvement in soap dispensing devices in which a cake of soap is under more or less constant feeding pressure, which soap, through control of a manually operable element, is delivered through the outlet of the device in a finely comminuted form.

In devices of this character, it is important that the soap material be delivered in as fine a form as possible and that the operation on the soap body or cake to form it into the fine powder be of a character to insure as complete a use of the entire cake as possible. To secure this result it has been heretofore proposed to subject the surface of the soap cake to a cutting or abrading action, acting on the cake in one direction only, with the result that the particles so delivered are somewhat coarse and not as easily soluble in water as the finer powder, and the cake, in those portions not immediately attacked by the cutters, will flake off or break in larger particles, which is objectionable.

It is, therefore, the primary object of the present invention to provide a cutter peculiarly adapted for the treatment of the soap cake in that in its operation it not only cuts into the cake vertically but also horizontally, thus insuring that the full surface area of the cake is similarly operated on and that the particles delivered as a result of the cutting operation are in the finest powdery form to insure easy and speedy solubility.

Devices of this character are usually in the form of containers fixed to the walls of public wash rooms and the like and unless provision is made to the contrary, the soap cakes are frequently extracted in their entirety from the device by unauthorized persons. This in some instances has been overcome by the use of a key-controlled lock which, while it may function to prevent extraction of the soap cake, requires that the person authorized to renew the soap make more or less frequent inspection to determine whether or not the soap requires renewal, coupled of course with the use of a key or other unlocking element.

A further object of the invention is to provide a means for automatically notifying any

interested party of the fact that the soap in the container has been exhausted. This means includes a lock for the closure, with a spring hinge connecting the closure with the container. The lock is arranged to be automatically released by cooperation with the plunger when the latter has reached a position incident to the complete use of the soap cake. The automatic release of the lock causes the spring hinge to move the closure to open position, thus notifying both the attendant and anyone desiring to use the device that the soap is exhausted.

The invention is illustrated in the accompanying drawing in which:

Figure 1 is a view in elevation of the improved soap dispensing device, interior parts being shown in dotted outline.

Figure 2 is a section on line 2-2 of Figure 1.

Figure 3 is an enlarged front elevation of the cutter.

Figure 4 is a side view of one of the disks making up the cutter.

Figure 5 is a broken elevation from the inner side of the closure to illustrate more particularly the locking means and the automatic operator therefor.

Figure 6 is a broken sectional view showing a slightly modified form of cap.

It is an essential purpose of the present invention to provide a simple, thoroughly effective device of this character which may be economically produced and which as a result will permit the use of such devices to an extent now prohibited by the first cost thereof. To this end, it is to be understood that the various parts of the device now to be described are constructed of stampings and are formed so that but the minimum mechanical operation other than a stamping process is necessary in the construction of the device.

In the preferred embodiment of detail, as illustrated in the accompanying drawing, the construction provides a casing 1, preferably rectangular in cross section, formed with front and rear walls 2 and side walls 3, the side walls 3 throughout their lower portions being extended into rounded or circular

form at 4 and the front and rear walls being curved in coincidence with the edges of the side walls, as at 5, to form a more or less circular enlargement 6 at the lower end of the casing which provides a delivery outlet 7.

The front wall 2 of the casing 1 is formed with an opening having a door or closure 8 hinged at the upper end, as at 9, and provided at its lower end with an operating knob 10 or handle 10. The hinge 9 is of the spring type capable of opening and raising the closure if the latter is unlocked. Within the upper rectangular portion of the casing is mounted a follower 11, corresponding in contour but of less sectional dimensions than the casing. The follower is preferably hollow to permit it to be formed as a stamping, and a spring 12 bears between the upper or cap end 13 of the casing and the plunger, the spring being preferably of a diameter to permit its lower end to seat within the plunger.

A rotary cutting and comminuting element is mounted in the circular enlargement 6 of the casing. This element forms one of the essential features of the invention and includes a shaft 14 mounted transversely of the cylindrical casing enlargement and extended at one end in the form of a crank 15 through which the shaft may be turned at will. On the shaft, within the circular enlargement, are arranged disks 16 of a diameter somewhat less than that of the circular enlargement 6 having their peripheral edges preferably formed as a series of teeth 17. Each disk is divided on a diametric line, as at 18, the divisions extending from the peripheral edge of the disk to a point short of the center of the disk. The disks are arranged upon the shaft 14 and spaced by sleeves 19, the arrangement being such that the disks and shaft constitute a unitary structure through any appropriate fastening means.

Through the line of division 18, each disk is divided substantially into halves and each half is twisted from its normal plane into a plane marginally coincident with the edges of immediately adjacent disks on each side. Thus, each half of each disk is deflected at relatively reverse inclinations from the shaft 14 so that one portion of a particular disk has its respective ends in coincidence with the ends of an opposing portion of each of two adjacent disks. There is thus provided a cutting element of substantially spiral form constructed of flat disks and having a substantially unbroken toothed margin. The disks, of course, are very thin so that they in effect present cutting teeth.

The closure 8 is provided with a locking element in the form of a bar 20 pivotally connected at 21 and formed at the opposite end with a depending lip portion 22 preferably guided through a pin and slot con-

nection 23 with the closure. The lip portion 22 is designed to seat by gravity in rear of the lower margin of the closure opening in the front wall 2, in which position it is obvious that the closure 8 is locked against opening.

As the follower 11 moves downwardly, it will eventually reach a point at which little or no soap remains in the cake. Just prior to this position of the follower, a projection 24 on such follower engages that end of the bar 20 opposite the lip 22, and as the follower continues its movement, it is apparent that the bar 20 will be swung on its pivot 21 to withdraw the lip 22 from locking cooperation with the casing wall. The closure 8 is then free and is swung open by spring hinge 9 to permit the insertion of a fresh cake of soap.

A cake of soap, indicated at 25, is placed beneath the follower 11 which, under the influence of the spring 12, forces the soap into contact with the cutting and comminuting element. Whenever it is desired to obtain a quantity of soap, the crank 15 is turned, causing the toothed edge of the now spiral cutter to engage in and operate on the lower surface of the cake of soap. In this operation, the teeth 17 will, of course, cut into the mass of soap in a vertical direction but as these teeth are, during this vertical cut, being moved transversely of the cake of soap, it follows that the cutting operation is taking place simultaneously in two directions relative to the cake of soap and hence the material of the soap cake is divided into the finest powder-like flakes which will gravitate through the outlet 7 onto the hand or onto any article placed therebeneath.

It is to be particularly noted that the cutting and comminuting element is formed of disks readily and conveniently stamped from metal and easily and simply arranged in proper form to provide the spiral element desired. The characteristic function of this element in cutting the soap cake in two angularly related directions at the same time insures a proper comminuting of the material to present the finest powdery or flaky condition, and at the same time insures the cutting away of the full area of the lower surface of the cake. That is to say, there are no margins, projections, or other parts of the cake left in any one plane following the operation of the cutter, and hence a subsequent operation does not tend to break off larger undesirable portions of the soap with consequent loss of material and disadvantageous solubility in use.

In connection with the type of cutting and comminuting element described, it is, of course, understood that the disks may be in the form of independent knives having sharpened edges or may be in other appropriate detail structure so long as the desirable func-

tion of cutting into the cake of soap in each of two right angularly related directions in a single operation of the element is maintained.

3 After the soap cake has been introduced, it is apparent that it will remain in position locked against extraction against unauthorized persons until the limit of its use has been reached, at which time the closure 8 will be automatically unlocked to permit the introduction of a fresh cake.

The soap dispensing device as a whole is preferably provided with a bracket 26 by which it may be secured to a fixture.

13 If it is desired to dispense with the closure 8 and introduce the soap through the upper end of the casing 1, the cap, similar to the cap 13 in the preferred form, may be constructed as indicated in Figure 6. As 20 shown here, the cap 27 is adapted to telescope the upper end of the casing 1, being provided with walls 28 on two opposing sides which are formed with openings 29 to snap over pins 30 on the walls 3, the lower ends of the 25 extended walls being out-turned at 31 to provide for disengaging the cap at will. Here, the cap may be removed, the spring 12 and follower 11 lifted out, the fresh cake of 30 soap applied, and the follower, spring and cap returned to operative positions.

It will be apparent from the construction that practically all parts of the device are of a nature to permit them to be readily stamped from sheet material. This materially facilitates the manufacture of the device and so cheapens its first cost as to permit it to provide an extremely simple, serviceable and readily salable article incident to its economic production.

40 What is claimed to be new is:

1. A cutter for soap dispensing devices, comprising a shaft mounted for rotation, a series of disks mounted on the shaft and held in relatively spaced relation, the disks being 45 divided diametrically from their free edges to a point short of the center, the respective halves of each disk as thus provided being reversely twisted to cause the peripheral edge of one half of each disk to register with the peripheral edges of the opposing halves 50 of adjacent disks, whereby to present a spiral edge.

2. A soap dispensing device of the type 55 wherein soap is arranged for movement in one direction for comminuting purposes, a cutter for comminuting the soap including a shaft mounted for rotation, and a plurality of disks arranged in spaced relation on the shaft and having their peripheral edges serrated, each disk being divided inwardly from its peripheral edge and the portions of the disks beyond the line of division being oppositely twisted to arrange the peripheral edge of each twisted portion at an angle other than a right angle to the axis of the shaft,

the angular relation of the twisted portions of the disks being such as to substantially register the peripheral lines of such twisted portions of one disk into the peripheral lines of the twisted portions of the adjacent disks, 70 whereby to present a cutter having a spirally arranged serrated edge.

3. In a soap dispensing device of the type wherein means are provided for feeding a cake of soap longitudinally of a casing, a 75 cutter for comminuting the soap, said cutter including a shaft mounted for rotation in the casing, a plurality of disks secured on the shaft and having cutting elements on the peripheral edges, each of the disks being 80 divided on a diametric line inwardly from the peripheral edge and terminating short of the bearing on the shaft to form each disk into approximately equal sections, each section of each disk being reversely turned at 85 an angle to the normal plane of the disk and to an extent to cause the peripheral edge at the juncture of the line of division to register with the similar point of one of the twisted sections of the next adjacent disks, whereby 90 to present an uninterrupted spiral cutting edge throughout the axial length of the cutter.

4. A cutter for soap dispensing devices 95 including a plurality of disks supported in axial spaced relation, adjacent portions of each disk being offset from the normal plane of the disks in opposite directions, the similarly directed offset portions of each disk 100 aligning with the oppositely directed offset portions of adjacent disks, such offset disk portions forming uninterrupted continuations of the peripheral portions of adjacent disks arranged at an inclination to the normal plane of the disks. 105

In testimony whereof I affix my signature.
